UNITED STATES PATENT OFFICE.

GEORGE E. GOUCHER, OF PHILADELPHIA, PENNSYLVANIA.

DESIGN FOR FRINGE.

SPECIFICATION forming part of Design No. 13,894, dated May 8, 1883.

Application filed February 8, 1883. Term of patent 14 years.

To all whom it may concern:

Be it known that I, GEORGE E. GOUCHER, a citizen of the United States, residing in the city and county of Philadelphia, and State of Pennsylvania, have invented and produced an original Design for Fringe, of which the following is a specification, reference being had to the accompanying drawings, forming part thereof.

10 Of the drawings, Figure 1 is a front elevation of a fringe embodying my design. Fig. 2 is a cross-section of the pendant.

In the drawings, A are pendants, respectively in alternate and adjacent pairs, of the form of spirally-fluted cylinders and of hexagonal parallelopipedons, 15 B, and attached to any suitable heading, C.

I claim—

1. A design for a fringe, consisting of a heading, and of pendants, respectively in alternate 20 and adjacent pairs, of the form of spirally-fluted cylinders and of hexagonal parallelopipedons, as shown and described.

2. A design for a fringe, consisting of a heading, and of pendants, respectively in alternate 25 and adjacent pairs, of the form of spirally-fluted cylinders and of hexagonal parallelopipedons, and all of which are ornamented with balls, as shown and described.

In testimony whereof I have hereunto signed 30 my name this 29th day of January, A. D. 1883.

GEORGE E. GOUCHER.

In presence of—

J. BONSALL TAYLOR,
JOHN JOLLEY, Jr.
